UNITED STATES PATENT OFFICE.

MAX SCHÄFER, OF STUTTGART, GERMANY, ASSIGNOR, BY MESNE ASSIGNMENTS, TO AMERICAN BOSCH MAGNETO CORPORATION, OF NEW YORK, N. Y., A CORPORATION OF NEW YORK.

DISTRIBUTER FOR HIGH-TENSION IGNITING DEVICES.

1,337,329.

Specification of Letters Patent.

Patented Apr. 20, 1920.

Application filed June 27, 1918. Serial No. 242,245.

To all whom it may concern:

Be it known that I, MAX SCHÄFER, a subject of the German Emperor, residing at and whose post-office address is Stuttgart, 5 Johannesstrasse 96, Germany, have invented certain new and useful Improvements in Distributors for High-Tension Igniting Devices; and I do hereby declare the following to be a full, clear, and exact description 10 of the invention, such as will enable others skilled in the art to which it appertains to make and use the same.

The present invention relates to distributors for high tension ignition systems associated with multicylinder internal combustion engines, and particularly to gap distributors in which the sparking element of the rotor rotates or otherwise moves in close proximity to, but out of contact with the 15 series of sparking elements of spark plug terminals of the distributor, that is it provides a gap in passing or rotates in spaced coöperation with the terminals, to which are connected the wires leading to respective 20 spark plugs in the engine cylinders.

Heretofore it was necessary to use for the 25 sparking element an expensive metal as nickel in order to withstand oxidization so well as not to require too frequent renewals due to pitting and burning thereof upon 30 sparking and arcing upon passage of ignition currents between the rotor element and each of the spark plug terminal elements in turn. Not only does the expensive metal 35 increase the cost of the distributor and especially the renewals therefor to an appreciable extent, but the arrangement interferes with the continued effectiveness of the magneto or battery ignition system of 40 which the distributor is a vital part.

In place of an expensive metal capable of 45 withstanding oxidization to a high degree, I use for the sparking elements a cheap metal, as iron, which is easily oxidizable, that is one which withstands oxidization to a materially less degree than nickel, but I 50 eliminate the frequent renewals that would otherwise be necessary by providing each spark plug terminal, or the rotor, but preferably both of those parts of the distributor, with an adjustable sparking element so as to have a plurality of different positions of coöperation. Thus after one part of the

sparking surface of the element becomes pitted or burned away in operation, another 55 part may be brought into coöperation, and so on until the whole of the sparking surface capable of coöperation is unfit for further operation. Preferably the sparking element of each spark plug terminal, or of the 60 rotor, or of both, has sparking edges, and where the sparking edges are provided on the sparking elements of both the rotor and the spark plug terminals, those edges are arranged to extend at an angle to each other 65 in coöperation, so as to better maintain a fixed gap length.

The sparking element of each spark plug terminal, or of the rotor, may have the form of a cylinder, disk, polygon or any suitable 70 body, and either or both may be adjustable at will or freely rotatable in order to bring different parts of its sparking surface, or different sparking edges, into coöperation.

The foregoing features may be variously 75 combined in accordance with my invention, a number of the possible forms of construction and arrangement of the sparking elements being shown in the accompanying drawings, Figures 1 to 12, illustrating different embodiments.

In each of the embodiments illustrated, the distributor disk *a* of insulating material has embedded in it a series of spark plug terminals *b* each having an iron sparking 85 element *c* coöperating with an iron sparking element *c'* of a rotor adapted to be rotated or otherwise moved by the engine to a fixed speed ratio determined in accordance with well known principles. Each wire *d* leading 90 to a spark plug in an engine cylinder in the well known way is connected to the sparking element of an individual spark plug terminal of the distributor by a screw *f*.

In Fig. 1 the cylindrical sparking element *c* is held in adjusted position against its spark plug terminal *b* by a screw, and connection is made to the conductor of the wire *d* by the screw *f*. As in the remaining 95 embodiments illustrated, excepting in Fig. 6, the sparking surface of the element *c* has a large number of sparking edges milled axially along the outer periphery thereof. The sparking element *c* may be adjusted at will whenever the active edges become pitted 100 or burned away by loosening the screw hold-

ing it against the spark plug terminal *b*, turning it to a new position of coöperation with the sparking element *c'* of the rotor, and finally tightening the screw.

5 In Fig. 2, the cylindrical head *c* of the screw forms the adjustable sparking element of the spark plug terminal, the washers *g* being removed *seriatim* and the screw turned to a new tightened position to bring different 10 sparking edges into coöperation with the sparking element of the rotor.

In Fig. 3, the head *c* of the screw forms the sparking element and the shank *f* supports it in adjusted position and also pierces the wire *d* to connect them electrically.

In Fig. 4, the sparking element *c* is loosely mounted on a stud screw so as to freely turn in operation as a result of vibration, the passage of sparks, and upon being cleansed. 20 In this way the entire sparking surface is burned away more uniformly and without manual adjustment.

In Fig. 5 also, the sparking element *c* is freely rotatable but the screw *f* supports it as well as connecting it directly to the wire *d*.

In Fig. 6, the sparking element *c* has the form of a polygon and is locked in adjusted position on the screw *f* by the screw *h*.

In Fig. 7, the wire leading to the spark 30 plug is connected to the spark plug terminal *b* by a binding post, the sparking element *c* being held in adjusted position by a screw.

In Fig. 8, the sparking element *c* is held in adjusted position by a spring and engaging 35 notches, as shown.

In Fig. 9, the wire *d* is connected to the spark plug terminal *b* by the screw *f* entering from the rear of the distributor disk *a*.

In Fig. 10, the sparking element *c* is freely 40 rotatable on a pin extending between the prongs of a yoke of which the screw *f* is a part.

In Fig. 11, the nuts *i* of the binding posts extend around the rear face of the distributor disk *a* instead of around the outer periphery thereof as in Fig. 10.

In Fig. 12, the spark plug terminal *b* is angle shaped, one limb of which carries the 50 sparking element *c* and the other limb of which carries the connecting screw *f*.

In all of these embodiments the sparking element *c'* of the rotor may be a cylinder, disk, polygon, or other suitable body, either solid or laminated, and may be adjustable 55 or freely rotatable on the rotor of the distributor. So also, its sparking surface may likewise be smooth, chased, or formed of milled edges. Where both the sparking elements of the rotor and the spark plug elements have edges, they are preferably arranged at right angles to each other in coöperation so that in any position of adjustment of either, the gap between them is of fixed length. For this reason, and also be- 60 cause sparking is facilitated, the sparking 65

elements preferably have sparking edges arranged in this way, as shown in Figs. 3, 10, 11 and 12.

In Fig. 3, the sparking element *c'* of the rotor is freely rotatable in the yoke *e*, as 70 may also be the case in all of the embodiments, excepting Fig. 12 in which the sparking element is formed by the head *c'* of a screw adapted to be screwed into and out of the rotor for adjustment. In Figs. 3, 10 75 and 12, the rotor of the distributor is shown on a horizontal axis whereas in Fig. 11, it is shown on a vertical axis. In Figs. 11 and 12, the axes of the adjustable elements *c* are vertical, whereas in the remaining embodiments the axes thereof are horizontal. 80

It is obvious that various arrangements other than those illustrated are included within the invention, the sparking elements being capable of rearrangement and change 85 in a great variety of ways, the essential feature being that either sparking elements *c* of the spark plug terminals or the sparking elements *c'* of the rotor, or both, are adjustable to bring different parts of their 90 sparking surface, or different sparking edges, into coöperation so that easily oxidizable metal, as iron, may be used in place of the more expensive nickel hertofore used for this purpose. 95

Having thus described my invention, what I claim is:

1. In a gap distributor, a series of spark plug terminals each having an adjustable element with sparking edges of easily oxidizable metal, and a rotor having a sparking element arranged to provide a gap in passing said terminals, each adjustable element being rotatably supported to bring different sparking edges into coöperation 100 with the sparking element of the rotor. 105

2. In a gap distributor, a series of spark plug terminals each having a rotatably supported element with sparking edges of easily oxidizable metal, and a rotor having a 110 sparking edges arranged to extend at an angle to the sparking edges of said terminals in spaced coöperation therewith.

3. In a gap distributor, a series of spark plug terminals each having a freely rotatable element with sparking edges of easily oxidizable metal, and a rotor having a 115 sparking element arranged to provide a gap in passing the sparking edges of said terminals. 120

4. In a gap distributor, a series of spark plug terminals each having a sparking element, and a rotor having a rotatably mounted element with sparking edges of easily oxidizable metal arranged to provide a gap 125 in passing the sparking elements of said terminals.

5. In a gap distributor, a series of spark plug terminals each having an element with 130

sparking edges, and a rotor having a rota-

tably mounted element with sparking edges of easily oxidizable metal arranged to extend at an angle to the sparking edges of said terminals in spaced coöperation there-
5 with.

6. In a gap distributer, a series of spark plug terminals each having an adjustable element with a sparking surface of easily oxidizable metal, and a rotor having an ad-
10 justable element with a sparking surface of easily oxidizable metal arranged to provide a gap in passing the adjustable elements of said terminals, both adjustable elements be-
ing rotatably supported to bring different
15 parts of their sparking surfaces into coöp-
eration.
7. In a gap distributer, a series of spark plug terminals each having a rotatably sup-
ported element with sparking edges of eas-
20 ily oxidizable metal, and a rotor having a

rotatably supported element with sparking edges of easily oxidizable metal, the spark-
ing edges of the rotor element being ar-
ranged to extend at an angle to those of the
terminal elements in spaced coöperation 25
therewith.

8. In a gap distributer, a series of spark plug terminals each having a sparking ele-
ment, and a rotor having a freely rotatable
element with sparking edges of easily oxi-
dizable metal arranged to provide a gap in
passing the sparking elements of said ter-
minals. 30

In testimony whereof I affix my signature in presence of two witnesses.

MAX SCHÄFER.
